CLAIM

The ornamental design for a pulled cart, as shown and described.

DESCRIPTION

FIG. 1 is a perspective view of a pulled cart showing the new design and taken from the left side; FIG. 2 is a left side elevational view thereof showing a portion of the tow bar broken away for convenience of illustration;

FIG. 3 is a top plan view thereof;

FIG. 4 is a front elevational view thereof, it being understood that the rear is substantially a mirror image of the front except for the omission of the tow bar and the heads of the screws being seen rather than the nuts used with said screws;

FIG. 5 is a bottom plan view thereof.
